UNITED STATES PATENT OFFICE.

JOSEPH THOMAS, OF ABERDEEN, WASHINGTON.

LAST FOR SHOES AND SANDALS.

Application filed August 22, 1922. Serial No. 583,537.

To all whom it may concern:

Be it known that I, JOSEPH THOMAS, a citizen of the United States of America, and a resident of Aberdeen, in the county of 5 Grays Harbor and State of Washington, have invented a new and Improved Last for Shoes and Sandals, of which the following is a description.

My invention relates to lasts especially 10 useful for sandals but adapted to be employed also for shoes.

The general object of my invention is to provide a last adapted to be placed against the shoe at the exterior instead of being 15 inserted in the shoe.

Most sandals have the sole fastened with wire staples and in repair work thereon sewing is made difficult owing to the needle engaging the staples which results in frequent 20 breaking of the point of the needle. It is therefore an object of my invention to provide for a last that will enable the sole to be fastened neatly, and practically invisibly, by nailing with the edge of the sole 25 placed against the last disposed at the exterior of the sandal.

The manner and means by which the above and other objects are attained will clearly appear as the description proceeds.

Reference is to be had to the accompanying drawings forming a part of this specification, it being understood that the drawings are merely illustrative of practical examples of the invention.

Figure 1 is a plan view of a last formed in accordance with my invention;

Figure 2 is a side elevation thereof supported on a standard, part of the last being broken away;

Figure 3 is a plan view of a portion of the last showing the manner of disposing a sandal or shoe against different edge portions of the last;

Figure 4 is a vertical section as indicated 45 by the line 4—4, Figure 3;

Figure 5 is a plan view of my improved last made in a different shape from that shown in Figures 1 to 4;

Figure 6 is a detail in vertical section on 50 the line 6—6, Figure 5.

Referring at first more particularly to the form shown in Figures 1 to 4, my improved last is made with various side edges to suit the different curves presented by a sandal or 55 shoe, there being shown at opposite sides grooves 10, 11 adjacent the side edges, said

grooves and others as hereinafter referred to being adapted to receive the rim or edge portion of sandals for example. The arrangement furthermore may be used for nailing 60 ribs in welted shoes, as well as for flattening out all welts when the welts are uneven and in the half-soling of women's narrow welted shoes, the last is particularly useful as the welt can be flattened out and room can be 65 made for the lip of the stitching machine to travel thereon, thereby enabling a neat job to be performed especially in the half-soling of women's shoes because the welts can be conveniently disposed.

The grooves 10, 11 are provided with a view to the fastening of the inner and outer sides of the sole. A groove 12 is provided at an edge portion of the last and adapted to be employed when securing the shank of 70 the shoe. An additional long curve 13 is formed at another side of the last and presents a different curve from the grooves 10, 11 to suit curves of different shoes, and different parts of a shoe. At another side of 75 the last approximately opposite the groove 13 I form a groove 14 of pronounced curvature adapted for use in fastening at the heel or toe of the sandal or shoe. For operating on exceptional parts of the sole a short 80 groove 15 is provided having a slight curvature and with a similar object in view a flattened straight portion 16 is provided between the adjacent terminals of the 85 grooves 11. The adjacent sides of the 90 grooves 10 and 14 are convergent and merge at the front of a horn-like member 17 which has a beveled top upper surface. A beveled surface 18 is provided also adjacent to shank groove 12 for the proper positioning of the 95 shoe or sandal. I have shown the last as provided with a socket 19 at the under side adapted to receive the standard 20 of a stand or jack. In the top of the last within the groove referred to is a depression 21 to 100 hold nails.

Sandals or shoes may be positioned as indicated at A and B, the one, A, being positioned for operating on the toe while the other, B, is positioned at the groove 10 for 105 nailing the sole at a side thereof. With the improved last the sole is secured advantageously in position by the use of nails indicated at C, the nails being clinched by contact with the last at the bottoms of the 110 grooves. Preferably, the nails are so driven as to clinch outwardly.

In Figure 5 the last is formed with side grooves 110, 111 for the side curves of the sandal with a groove 112 for the shank and a groove 114 for the heel or toe. In addition at the sides of the pronouncedly curved groove 114 are a short curved groove 115 and a short straight groove 116 for operating on a sole at exceptional points thereon. The grooves may be made horizontal or advantageously sloping inwardly as shown in Figure 6 looking to the effective clinching of the nails. The edges of the last at those grooves provided for operating on the last at the side curves or at the heel or toe are concaved while the last adjacent those grooves 12 or 112 for operating on the shank are convexed. In Figure 5 the numeral 121 indicates a depression in the last to hold nails.

I would state in conclusion that while the illustrated examples constitute practical embodiments of my invention, I do not limit myself strictly to the exact details herein illustrated, since, manifestly, the same can be considerably varied without departure from the spirit of the invention as defined in the appended claims.

Having thus described my invention, I claim:

1. A last adapted to be positioned against the exterior of a shoe or sandal and having means to receive an edge portion of the sole to enable the sole to be fastened with nails while disposed against the last.

2. A last adapted to be positioned against the exterior of a shoe or sandal and having edge portions to conform to the lines of the different portions of the shoe.

3. A last presenting concave edge portions and grooved adjacent to said edge portions, said last adapted to be employed at the exterior of a shoe.

4. A last presenting concave edge portions, said last adapted to be employed at the exterior of a shoe, and said edge por-

tions conforming to the curvature of the shoe at the inner and outer sides thereof.

5. A last presenting concave edge portions, said last adapted to be employed at the exterior of a shoe, and said edge portions conforming to the curvature of the shoe at the inner and outer sides thereof, said last furthermore having an edge portion of more pronounced curvature adapted to conform to a shoe or sandal at the heel or toe.

6. A last presenting concave edge portions, said last adapted to be employed at the exterior of a shoe, and said edge portions conforming to the curvature of the shoe at the inner and outer sides thereof, said last furthermore having an edge portion of more pronounced curvature adapted to conform to a shoe or sandal at the heel or toe; the surface of the last immediately adjacent said edge portions being grooved.

7. A last having a convex edge portion adapted to be disposed against a shoe or sandal at the shank thereof at the outside of the shoe.

8. A last having a convex edge portion adapted to be disposed against a shoe or sandal at the shank thereof at the outside of the shoe, said last having a groove adjacent to and following the curvature of said edge portion.

9. A last adapted to be positioned against the interior of a shoe or sandal and having edge portions to conform to the lines of the different portions of the shoe, said last having grooves adjacent to and following the curvature of said edge portions.

10. A last adapted to be positioned against the interior of a shoe or sandal and having edge portions to conform to the lines of the different portions of the shoe, said last having grooves adjacent to and following the curvature of said edge portions, the bottoms of said grooves sloping inwardly.

JOSEPH THOMAS.
